IMIDAZOLINIUM COMPOUNDS

Horace A. Shonle, Indianapolis, and Edwin R. Shepard, Beech Grove, Ind., assignors to Eli Lilly and Company, Indianapolis, Ind., a corporation of Indiana

No Drawing. Application July 19, 1946,
Serial No. 684,779

5 Claims. (Cl. 260—309.6)

1

This invention relates to a group of new organic compounds and more particularly to new substituted dihydroimidazolium compounds. This application is a continuation-in-part of our prior application Serial No. 605,191, filed July 14, 1945, now abandoned.

These new substituted dihydroimidazolium compounds have surface tension depressing and bacteriostatic properties, and certain preferred compounds have therapeutic value for combating various bacterial invasions.

By this invention we have provided new compositions of matter which may be represented by the following formula:

wherein R is an aliphatic hydrocarbon residue having a carbon content within the range of 8 to 18 carbon atoms, R₁ and R₂ are the same or different aliphatic hydrocarbon radicals each having from 1 to 7 carbon atoms, the total number of carbon atoms in R and R₁ being from 10 to 25; X is an anion; and n is an integer from 1 to 3 inclusive.

The R substituent may be a particular hydrocarbon radical, or it may be a mixture corresponding to a commercial product from which it is derived, for example, one comprising a mixture of several homologous hydrocarbon compounds of differing numbers of carbon atoms within the range of 8 to 18 carbon atoms, or one consisting mainly of a particular hydrocarbon compound with smaller amounts of close homologues of such compound copresent. For example, the R substituent may be derived from the commercial alcohol "Lorol," which is a mixture of alcohols of from 8 to 18 carbon atoms, in which case the R substituent may be considered to comprise a corresponding mixture. The R₁ and R₂ substituents may also contain such variations, but in most cases substantially pure starting compounds will be convenient for these shorter-chain substituents.

The compositions of matter of our invention may be regarded as comprising positively charged dihydroimidazolium cations which are substituted by aliphatic hydrocarbon radicals and which are combined with negatively charged anions. The aliphatic hydrocarbon groups may be selected from straight chain saturated,

2

branched chain saturated, and straight and branched chain unsaturated groups. The negatively charged anion associated with the dihydroimidazolium cation may be any one of a number of negative ions such as, for example, the chloride, bromide, sulfate, acetate, or phosphate ions. By way of example, and referring to the above structural formula, when R is a dodecyl group, R₁ an isoamyl group, R₂ an allyl group, X a sulfate ion, and n is 2, the compound is di(1-dodecyl-2-isoamyl-3-allyl-4,5-dihydroimidazolium) sulfate.

In compounds of this invention the number of carbon atoms contained in the two groups R and R₁ ranges from a total of 10 to about 25 carbon atoms. The following example illustrates this limitation: When R₁ is a hydrocarbon group containing 1 carbon atom, R must be a hydrocarbon group containing at least 9 carbon atoms, but it may contain any number up to its own limit of 18 carbon atoms.

It should be noted that two isomeric forms of our compounds exist simultaneously because of a dynamic equilibrium. Thus, compounds of our invention may be represented by either of the following formulas:

Formula A

Formula B

wherein R, R₁, R₂, X and n have the same significance as before. In Formula A, the nitrogen at position 1 is tertiary, and the nitrogen at position 3 is quaternary. In Formula B, the nitrogen at position 1 is quaternary, and the nitrogen at position 3 is tertiary. In the specification and claims we employ for convenience Formula A, wherein R is attached to the tertiary nitrogen at position 1, and R₂ is attached to the quaternary nitrogen at position 3. It will be understood that both isomers illustrated are to be considered as within the scope of this invention.

The compounds of this invention have several fields of utility. For example, they are effective in reducing the surface tension of aqueous solutions, and have bacteriostatic properties. Additionally, certain preferred compounds have therapeutic qualities which make them suitable for application in the treatment of various bacterial invasions. These preferred compounds are those of

the foregoing formulas in which the R substituent is an aliphatic hydrocarbon residue having from 8 to not over 13 carbon atoms, the sum of the carbon atoms in R and R₁ is from 10 to 17, and the sum of the carbon atoms in R, R₁, and R₂ is not greater than 18. These preferred compounds are distinguished by their antibacterial properties and their low hemolytic effect. For example, a compound in which R is a 14-carbon radical and R₁ and R₂ are both methyl is more than four times as hemolytic as saponin, whereas a corresponding compound in which R is a 12-carbon radical is less than one half as hemolytic as saponin.

Broadly, we may prepare the compounds embodied in our invention by reacting a suitably substituted dihydroimidazole with a member of the class of alkylating agents such as, for example, the nitrates, sulfates or halides of aliphatic hydrocarbons. Preferably, and because of their ready availability, we employ the halides—by which we mean the chlorides, bromides and iodides, and exclude the fluorides—and thus preferably form compounds in which the anion X⁻ is a halogen anion—by which we mean chloride, bromide or iodide. The reaction is effected by mixing the substituted dihydroimidazole with the halide of the aliphatic hydrocarbon, allowing any spontaneous reaction to subside and subsequently heating the mixture to complete the reaction. The product may be purified by recrystallization or precipitation from suitable solvents or mixtures thereof. The theoretical amount of the aliphatic hydrocarbon halide may be used but it is preferable to use an excess to assure completion of the reaction. The reaction is conveniently, although not necessarily, carried out in a closed system thus eliminating any loss of the aliphatic hydrocarbon halide by volatilization. If desired, a suitable non-reactive solvent such as, for example, alcohol or ethyl acetate may be used as a vehicle during the reaction.

In preparing the compounds of our invention there may be used as starting material a mixture of similarly substituted dihydroimidazoles. Thus for example, referring to the above formulas, a group of dihydroimidazoles wherein R is a mixture of aliphatic hydrocarbon radicals having from 8-18 carbon atoms and R₁ is an aliphatic hydrocarbon group containing not more than 7 carbon atoms, may be reacted with a halide of an aliphatic hydrocarbon such as methyl bromide to yield a mixture of the correspondingly substituted dihydroimidazolium bromides.

It should be noted that the compounds of our invention comprising both of two isomeric forms as mentioned heretofore may be prepared by either of two routes. A dihydroimidazole substituted by the groups R and R₁ may be alkylated with an R₂-containing alkylating agent. Likewise a dihydroimidazole substituted by the groups R₁ and R₂ may be alkylated by an R-containing alkylating agent. The same compound or mixture of compounds results when R, R₁, and R₂ are correspondingly identical in each alkylation reaction.

The compounds of our invention are salt-like and generally water-soluble, and consequently are subject to many of the ionic reactions which typify soluble inorganic salts. By anionic interchange reactions, one anion may be substituted for another. For example, by taking advantage of the lower solubility of a substituted dihydroimidazolium sulfate as compared with the solubility of the corresponding imidazolium chloride,

the sulfate may be crystallized preferentially from a solution containing the dihydroimidazolium, sulfate and chloride ions. Illustrating another method of effecting this conversion, an aqueous solution of substituted dihydroimidazolium halide may be shaken with substantially insoluble silver sulfate, whereby the halide ion is removed as insoluble silver halide leaving in solution the dihydroimidazolium sulfate. Additionally, ionic interchange may be effected through the hydroxyl ion as an intermediate. Upon shaking an aqueous solution of a substituted dihydroimidazolium halide with silver oxide, there is formed the corresponding soluble dihydroimidazolium hydroxide and insoluble silver halide. Treatment of the soluble dihydroimidazolium hydroxide solution with the appropriate acid forms the desired dihydroimidazolium compound.

The following examples illustrate our invention.

20

Example 1

1-n-decyl-2,3-dimethyl-4,5-dihydroimidazolium iodide represented by the formula

30 may be prepared from 1-n-decyl-2-methyl-4,5-dihydroimidazole and methyl iodide as follows:

1-n-decyl-2-methyl-4,5-dihydroimidazole was prepared by heating a mixture of 203 g. of N-acetyl ethylene diamine and 560 g. of finely powdered calcium oxide to 225-235° C. for 14 hours. After cooling to 90-100° C. the mixture was extracted with three 500 cc. portions of alcohol. The alcohol was evaporated and the residue upon distillation at 195-198° C. yielded 2-methyl-4,5-dihydroimidazole. A mixture of 50.4 g. of 2-methyl-4,5-dihydroimidazole, 52.8 g. of n-decyl chloride and 100 cc. of benzene was refluxed for seven hours and then cooled to 25° C. A solution of 24 g. of 50 percent sodium hydroxide solution in 150 cc. of water was added, the mixture filtered and the benzene layer separated from the filtrate. The benzene was removed in vacuo and the crude 1-n-decyl-2-methyl-4,5-dihydroimidazole distilled at 155-156° C./6 mm.

50 A cold mixture of 1.8 g. of 1-n-decyl-2-methyl-4,5-dihydroimidazole and 1.7 g. of methyl iodide was sealed in a tube and the tube was heated at 100-110° C. for two hours. The tube was then cooled to room temperature, its contents dissolved in about 40 cc. of boiling ethyl acetate, and the solution treated with decolorizing carbon and filtered. Upon cooling the filtrate to about 0° C., 1-n-decyl-2,3-dimethyl-4,5-dihydroimidazolium iodide precipitated. It was recrystallized from ethyl acetate whereupon it melted at about 103-104° C.

Example 2

1-n-decyl-2-n-amyl-3-methyl-4,5-dihydroimidazolium iodide represented by the formula

65 may be prepared by reacting 1-n-decyl-2-n-amyl-4,5-dihydroimidazole with methyl iodide as follows:

70 The 1-n-decyl-2-n-amyl-4,5-dihydroimidazole

used in the preparation was prepared by methods analogous to the preparation of 1-n-decyl-2-methyl-4,5-dihydroimidazole described in Example 1.

A cold mixture of 1.5 g. of 1-n-decyl-2-n-amyl-4,5-dihydroimidazole and 1.7 g. of methyl iodide was sealed in a tube. Upon warming to about room temperature the contents of the tube reacted spontaneously, after which reaction the tube was heated to 110° C. for one hour. The tube was then cooled to about room temperature, its contents dissolved in about 50 cc. of hot ethyl acetate, the solution treated with decolorizing carbon and filtered. Cooling to 0° C. produced no precipitate, whereupon petroleum ether was added to the solution to yield a precipitate of 1-n-decyl-2-n-amyl-3-methyl-4,5-dihydroimidazolium iodide which separated as an oil. The oil was purified by dissolving it in ethyl acetate, treating with decolorizing carbon, filtering and adding an excess of petroleum ether to reprecipitate the 1-n-decyl-2-n-amyl-3-methyl-4,5-dihydroimidazolium iodide as an oil which was dried in a vacuum desiccator over sulfuric acid.

Example 3

1-n-dodecyl-2,3-dimethyl-4,5-dihydroimidazolium iodide represented by the formula

may be prepared by reacting 1-n-dodecyl-2-methyl-4,5-dihydroimidazole with methyl iodide according to the method used in the preparation of 2,3-dimethyl-1-n-decyl-4,5-dihydroimidazolium iodide described in Example 1.

1-n-dodecyl-2,3-dimethyl-4,5-dihydroimidazolium iodide melted at about 120-121° C.

The 1-n-dodecyl-2-methyl-4,5-dihydroimidazole used in the preparation was prepared by a method analogous to that used in the preparation of 1-n-decyl-2-methyl-4,5-dihydroimidazole described in Example 1.

Example 4

1-n-tetradecyl-2,3-dimethyl-4,5-dihydroimidazolium iodide represented by the formula

may be prepared by reacting 1-n-tetradecyl-2-methyl-4,5-dihydroimidazole with methyl iodide by a method analogous to that used in the preparation of 1-n-decyl-2,3-dimethyl-4,5-dihydroimidazolium iodide described in Example 1.

The 1-n-tetradecyl-2,3-dimethyl-4,5-dihydroimidazolium iodide thus obtained melted at about 120-121° C.

Example 5

1-n-octadecyl-2,3-dimethyl-4,5-dihydroimidazolium iodide represented by the formula

may be prepared by reacting 1-n-octadecyl-2-methyl-4,5-dihydroimidazole with methyl iodide in a sealed tube according to the preceding examples.

The 1-n-octadecyl-2-methyl-4,5-dihydroimidazole used in the preparation is prepared by a method similar to that used in the preparation of 1-n-decyl-2-methyl-4,5-dihydroimidazole described in Example 1.

Example 6

A mixture of substituted dihydroimidazolium chlorides represented by the following formula

wherein R represents a mixture of aliphatic hydrocarbon radicals derived from a commercial mixture of monohydric alcohols such as "Lorol" may be prepared by the method of Example 1 except that in place of pure N-decyl chloride there are used chlorides derived from a commercial mixture of monohydric alcohols such as "Lorol" and in place of methyl iodide there is used methyl chloride.

We claim as our invention:

1. A composition of matter represented by the formula

in which R is an aliphatic hydrocarbon residue having a carbon content in the range of 8 to 18 carbon atoms, R1 and R2 are aliphatic hydrocarbon radicals each having from 1 to 7 carbon atoms, the sum of the carbon atoms in R and R1 being from 10 to 25, X is an anion, and n is an integer from 1 to 3 inclusive.

2. A composition of matter represented by the formula

in which R is an aliphatic hydrocarbon residue having a carbon content in the range of 7 to 18 carbon atoms, R1 is an aliphatic hydrocarbon radical having from 1 to 7 carbon atoms, R2 is a saturated aliphatic hydrocarbon radical having from 1 to 7 carbon atoms, the sum of the carbon atoms in R and R1 being from 10 to 25, X is an anion, and n is an integer from 1 to 3 inclusive.

3. A composition of matter represented by the formula

in which R is a mixture of aliphatic hydrocarbon radicals having from 8 to 18 carbon atoms, and Hx is a halogen anion other than fluorine.

4. A therapeutic composition comprising a composition of matter as defined in claim 1, in which the R substituent has not to exceed 13 carbon atoms, the sum of the carbon atoms in

the R and R₁ substituents does not exceed 17, and the sum of the carbon atoms in the R, R₁, and R₂ substituents does not exceed 18, and in which the anion X is a halogen anion other than fluorine.

5. 1-n-decyl-2,3-dimethyl-4,5-dihydroimidazolium iodide represented by the formula:
